231,513

GRIPPING DEVICE

John F. Adams, Chestnut Hill, Mass.
(1012 E. Wilson Ave., Apt. 5, Glendale, Calif. 91206)

Filed Apr. 3, 1972, Ser. No. 240,908

Term of patent 14 years

Int. Cl. D8—05

U.S. Cl. D8—14

FIG. 1

FIG. 2

FIG. 4

FIG. 3

FIG. 5

FIG. 1 is a view in perspective of the gripping device.
FIG. 2 is a plan view of the device.

FIG. 3 is a view in front elevation.

FIG. 4 is a view in perspective with the device inverted.

FIG. 5 is an enlarged perspective view of the device.

The broken line disclosure of a portion of a hand is
for illustrative purposes only.

I claim:

The ornamental design for a gripping device, substantially as shown and described.
